UNITED STATES PATENT OFFICE.

JOHN G. MUELLER, OF DAYTON, OHIO.

RAIL-BRACE.

1,226,571.

Specification of Letters Patent.

Patented May 15, 1917.

Application filed July 22, 1916. Serial No. 110,640.

To all whom it may concern:

Be it known that I, JOHN G. MUELLER, a citizen of the United States, residing at Dayton, in the county of Montgomery and State of Ohio, have invented certain new and useful Improvements in Rail-Braces, of which the following is a specification, reference being had therein to the accompanying drawing.

13. This invention relates to rail braces.
An object of the invention is to provide a rail brace which can be easily manipulated to adjust the rails to the desired gage and to retain them in such adjusted position.
15. It is also an object of the invention to provide a brace connecting the rails at the joints and fish plates to prevent movement of the ends of the rails forming each joint.

In the accompanying drawings, Figure 1 is an elevation of one form of brace taken transversely of the rails; Fig. 2 is a detail sectional view; Fig. 3 is a perspective view showing the application of one end of the brace to a rail joint; Fig. 4 is a view showing a slightly modified form of brace; and Fig. 5 is a view showing a second modified form of brace.

Referring to Figs. 1, 2 and 3 of the drawings I have shown a pair of rails 1 and 2 comprising joints 3. The joints are connected by fish plates 4 which are fastened to the rails in a well known manner. Adjacent each of the joints are clamping members 5 and 6 provided with clamping recesses 7 and 8 adapted to engage the base flange 9 of a rail and the flanges 10 of the fish plates. The lower portions of the clamping members comprise apertured lugs 11 and 12 and the ends of the sectional brace 13 are adapted to be threaded through the apertures thereof. These ends are sectional rods 14 and 15, which are provided with heads 16 and 17 at their outer ends against which the members 6 abut. The inner ends 45 of the sections 14 and 15 are screw-threaded, as shown at 18 and 19. Nuts 20 and 21 are mounted on these threaded portions and serve to clamp the members to the rails. Coöperating with these screw-threaded portions is an intermediate tube 22 having end portions 23 and 24 embracing the adjacent ends of the sections 14 and 15. The ends of this tube 22 are provided with screw-threaded nut portions 25 and 26 working 55 upon the screw-threaded portions 18 and 19. It will be seen that when the members

5 and 6 are securely clamped to the rails that the distance between the rails can be adjusted by rotating the member 22 which will draw the rails closer together and farther apart according to the direction of rotation. The threaded portions 18 and 19 of course must comprise right hand and left hand screw-threads.

Although I have shown my brace as applied to and connecting the rails adjacent the joints thereof it will be understood that it is within the scope of the invention to apply the same at any other points for connecting the rails.

The device that I have herein shown and described provides a very strong rigid construction for holding the rails in definite spaced apart relation, whereby the separating thereof is avoided but at the same time enables an adjustment to vary the gage thereof. Lock nuts 27 are provided to prevent the displacement of the parts.

Referring to Fig. 4 showing a modified form the rails 28 are each provided with 60 clamping members or jaws 29 and 30 having recesses 31 embracing the flange 32 of the rail. As in the form above described the clamping members or jaws of each rail are provided with downwardly extending apertured lugs 33 through which is threaded a sectional brace rod 34 provided with a head 35 at its outer end in engagement with the clamping jaw 30. The adjacent inner ends of the rod sections 34 are provided with 65 right and left hand screw threads 36 and 37 upon which a turn buckle 38 is adapted to work. The inner clamping members 29 can be adjusted and held against the rail flanges by means of the nuts 39 on the screw-threaded portions 36 and 37. The form shown here is in principle the same as the form shown in Fig. 1, the means for drawing the sections toward and away from each other being slightly different. The rods 70 being in section can be easily placed in position without the necessity of outside adjustment. In this way the inner clamping members or jaws only need be movable along the rod sections. The form shown in Fig. 4 75 may also be used at the joints and the clamping members thereof in such case would embrace the fish plates substantially as shown.

Referring to Fig. 5 illustrating probably the preferred form, the rails 40 thereof are 80 each provided with clamping members 41 and 42 having recesses 43 embracing the

base flange of the rail and the fish plates. In this form an integral single bracing rod 44 is used. This rod is provided with a head 45 at one end and adjusting nut 46 at the other. Upon this rod the clamping members 41 and 42 at each side are strung. The inner clamping members 41 are provided with tubular sections 47 screw-threaded into the clamping members at 48 and which encircle 10 the portions of the rod 44 located between the rails. The adjacent inner ends of the tubes are screw-threaded, as shown at 49, the screw-threads being left and right handed ones, and are connected by a screw-threaded 15 sleeve 50. This sleeve and the nut 46 can be adjusted to vary the gage or distance between the rails and also to securely clamp the parts together. When the sleeve 50 is rotated it will be seen that the clamping 20 members 41 will be moved into engagement with their rail flanges and the latter with the coöperating clamping members. When it is desired to vary the gage the sleeve 50 can be rotated in one direction or the 25 other and the nut 46 then tightened to hold the rails in adjusted position.

While I have shown and described one embodiment of my invention and several modifications thereof, it will be understood 30 that the same has been chosen for the purposes of illustration only, and that I do not desire to be limited to the details of construction shown and described, for obvious modifications will occur to a person skilled 35 in the art.

Having thus fully described my invention, what I claim as new and desire to secure by Letters Patent, is:—

1. The combination, with a pair of rails, of a brace rod, pairs of clamps loosely 40 mounted on said brace rod at the ends thereof, each pair of clamps embracing a rail, means on the ends of the brace rod for retaining the clamps thereon, and a single rotatable device interposed between the rails 45 for varying the gage thereof.

2. The combination, with a pair of rails, of clamping devices engaging the rails, a rod connecting the clamping devices and an adjustable tube encircling the rod and 50 engaging the adjacent clamping devices.

3. The combination, with a pair of rails, of clamping devices embracing each rail, a rod connecting said clamping devices, tubular sections embracing said rod and connected at their outer ends to the inner clamping devices and a sleeve mounted on the inner ends of said tubular sections for 55 adjusting the gage.

4. The combination, with a pair of rails, of clamping devices for said rails, a rod provided with an adjusting device strung through said clamping devices connecting them together, tubular sections embracing the rod and connected at their outer ends 60 to the inner clamping devices, and a sleeve having a screw-threaded engagement with the inner ends of said tubular sections.

In testimony whereof, I affix my signature.
JOHN G. MUELLER.
